DESIGN FOR A STUD BUTTON OR SIMILAR ARTICLE

Emanuel Jacobstein, New York, N. Y.

Application July 12, 1941, Serial No. 102,079

Term of patent 3½ years

To all whom it may concern:

Be it known that I, Emanuel Jacobstein, a citizen of the United States, residing in New York city, in the county of New York and State of New York, have invented a new, original, and ornamental Design for a Stud Button or Similar Article, of which the following is a specification, reference being had to the accompanying drawing, forming part thereof.

Fig. 1 is an elevational front view of a stud button or similar article showing my new design.

Fig. 2 is a perspective side view of Fig. 1, and Fig. 3 is another perspective view thereof.

The rear view of my design is conventional.

I claim:

The ornamental design for a stud button or similar article, substantially as shown and described.

EMANUEL JACOBSTEIN.
